CHILD'S FOLDABLE TOILET SEAT

Paul Wolcott, Jr., and Victor F. Wolcott,
San Diego, Calif.

Application September 16, 1946, Serial No. 697,200

5 Claims. (Cl. 4—239)

1

Our invention relates to a child's foldable toilet seat, more particularly for use in supporting children on conventional adults toilet seats and the objects of our invention are:

First, to provide a toilet seat of this class which is foldable and arranged to be carried in a very compact package so that a child's mother may readily set up the child's toilet seat on a conventional adult toilet seat when in public places;

Second, to provide a child's toilet seat of this class which provides sanitary seating for children when using public toilets;

Third, to provide a child's toilet seat of this class having flexible material on which a child may sit providing a very comfortable toilet seat;

Fourth, to provide a child's toilet seat of this class having means frictionally engageable with a conventional adult toilet seat for positively maintaining the child's toilet seat in proper position on the adult toilet seat;

Fifth, to provide a child's toilet seat of this class which is very strong and rigid in proportion to its weight;

Sixth, to provide a child's toilet seat of this class in which the foldable relationship of the seat frame maintains the resilient flexible covering in tight condition when the frame is in extended position; and

Seventh, to provide a child's toilet seat of this class which is very simple and economical of construction, efficient in operation, and which will not readily deteriorate or get out of order.

With these and other objects in view, as will appear hereinafter, our invention consists of certain novel features of construction, combination and arrangement of parts and portions as will be hereinafter described in detail and particularly set forth in the appended claims, reference being had to the accompanying drawings and to the characters of reference thereon forming a part of this application in which:

Figure 1 is a top or plan view of our child's toilet seat; Fig. 2 is a top or plan view thereof shown in partially folded condition; Fig. 3 is a top or plan view thereof shown completely folded; Fig. 4 is an enlarged sectional view taken from the line 4—4 of Fig. 1; Fig. 5 is an enlarged fragmentary sectional view taken from the line 5—5 of Fig. 1; Fig. 6 is a fragmentary sectional view taken from the line 6—6 of Fig. 4; and Fig. 7 is an enlarged sectional view taken from the line 7—7 of Fig. 2.

Similar characters of reference refer to similar parts and portions throughout the several views of the drawings.

2

The frame members 1, hinges 2, cover 3 and bearing members 4 constitute the principal parts and portions of our child's toilet seat.

The frame members 1 are preferably made of light tubing and are L-shaped in form, as shown best in Fig. 1 of the drawings. These L-shaped frame members 1 are secured together intermediate the corners of our child's toilet seat by means of the hinges 2. These hinges 2 are substantially U-shaped in cross section, as shown in Fig. 4 of the drawings, and are provided with hinged pins 2a extending through the ends of the frame members 1, as shown in Fig. 6 of the drawings. At the corners of our child's toilet seat formed by the frame members 1 are the bearing members 4. These bearing members 4 are positioned in surrounding relation with the frame members 1 at the corners thereof and are preferably made of flexible material such as rubber or the like which provides a bearing surface for our child's toilet seat when placed on an adult toilet seat for maintaining the same in secure engaged relation with said adult toilet seat. The cover 3 is a flexible cover preferably made of fabric or the like or, if desired, may be made of various synthetic resins or fabric material treated with various water-proofing materials. This cover 3 is provided with a central opening 3a therein, as shown best in Fig. 1 of the drawings, and is extended about the frame members 1, as shown best in Fig. 5 of the drawings. At the corners of our child's toilet seat the cover 3 is provided with cut-out portions 3b arranged to accommodate the bearing members 4, which extend outwardly of the cover 3. The cover 3 is provided with cut-out portions 3c arranged to accommodate the hinges 2 at two opposite sides of our child's toilet seat and is provided with cut-out portions 3d arranged to clear the remaining hinges 2 when in folded position. It will be here noted that the axis of the hinged pins 2a, in connection with the hinges 2, are parallel to each other at opposite sides of the child's toilet seat. As shown in Fig. 1 of the drawings, two of the hinges 2 at opposite sides of our child's toilet seat are provided with hinged pins substantially parallel to the plane of the cover 3. The two remaining hinges 2 are provided with hinged pins disposed in substantially perpendicular relationship to the plane of the cover 3. Thus, adjacent hinges 2 are provided with hinged pins perpendicularly disposed to each other.

The operation of our child's toilet seat is substantially as follows:

When our child's toilet seat is in extended condition, as shown in Fig. 1 of the drawings, it may be positioned on the upper surface of a conventional adult toilet seat and the bearings 4 engage the adult toilet seat and maintain frictional contact therewith whereby our child's toilet seat is maintained securely in position on the adult toilet seat. It will be noted that the bearing members 4 are preferably made of rubber or other material having a high co-efficient of friction relatively with the surfaces of conventional adult toilet seats. When the child's toilet seat, as shown in Fig. 1 of the drawings, is positioned on the adult toilet seat, the child may sit on the cover 3 over the opening 3a thereof in a very comfortable manner and sanitation of the child is maintained by the protection afforded by our child's toilet seat positioned over an adult toilet seat. When it is desired to fold our child's toilet seat into a compact package, the hinges 2 are first folded so that the child's toilet seat is in the position as shown in Fig. 2 of the drawings. Then, the remaining hinges 2 are folded on a perpendicular axis to the first folded relationship, as shown in Fig. 2 of the drawings, whereby a substantially rectangular package of small size, as shown in Fig. 2 of the drawings, is produced. When folded into the position, as shown in Fig. 3 of the drawings, the compact condition of the child's toilet seat lends itself to transportation in a mother's handbag or the like, providing a readily available toilet seat for children when in public places with their parents or guardians.

Though we have shown and described a particular construction, combination and arrangement of parts and portions, we do not wish to be limited to this particular construction, combination and arrangement, but desire to include in the scope of our invention, the construction, combination and arrangement substantially as set forth in the appended claims.

Having thus described our invention, what we claim as new and desire to secure by Letters Patent is:

1. In a child's toilet seat of the class described, the combination of a frame, said frame being rectangular in form and having four L-shaped frame members hinged together intermediate the corners of said seat at the straight sides of said toilet seat, four hinges connecting said frame members, two of said hinges having their axes at right angles to the plane of the seat and the other two of said hinges having their axes parallel to the plane of the seat, each hinge having an axis at right angles to the adjacent hinge axis, each hinge allowing pivotal movement in one direction only, and a flexible cover on said frame having an opening therein inwardly thereof.

2. In a child's toilet seat of the class described, the combination of a frame, said frame being rectangular in form and having four L-shaped frame members hinged together intermediate the corners of said seat at the straight sides of said toilet seat, a first pair of hinges on two opposing sides of the frame and a second pair of hinges on the other two opposing sides of said frame, said first pair of hinges connected

to pivot the frame about the longitudinal axis, the second pair of hinges connected to provide for the free ends of the folded seat to approach each other, a flexible cover on said frame having an opening therein inwardly thereof, and resilient bearing members surrounding said frame at the corner portions thereof arranged to provide frictional engagement with surfaces of adult toilet seats.

3. In a child's toilet seat of the class described, the combination of a frame flexible covering for said frame, having an opening therein, said frame composed of four L-shaped frame members and four U-shaped in cross section hinge members having hinge pins extending through adjacent ends of said frame members, two of said hinges having their axes at right angles to the plane of the seat, the other two of said hinges having their axes parallel to the plane of the seat, and all of said hinges having pivotal action in one direction only.

4. In a child's toilet seat of the class described, the combination of a frame, said frame being rectangular in form and having four L-shaped frame members hinged together intermediate the corners of said seat, said L-shaped frame members hingedly connected by two pairs of hinges, one pair of hinges having its axis at right angles to the plane of the seat and the other pair having its axis parallel to the plane of the seat, a flexible cover on said frame having an opening therein inwardly thereof and resilient bearing members surrounding said frame at the corner portions thereof arranged to provide frictional engagement with the surfaces of adults toilet seats.

5. In a child's toilet seat of the class described, the combination of a frame and a flexible covering for said frame having an opening therein, said frame composed of four L-shaped frame members and two pairs of hinges connecting said frame members, one of said pairs of hinges having its axis parallel to the plane of the seat, the other of said pair of hinges having its axis at right angles to the plane of the seat, said L-shaped frame members having U-shaped in cross section hinge members having hinge pins extending through adjacent ends thereof.
